UNITED STATES PATENT OFFICE.

CHESTER D. LIBBY, OF MELDEN, MASSACHUSETTS, ASSIGNOR TO A. C. LAWRENCE
LEATHER COMPANY, OF BOSTON, MASSACHUSETTS, A CORPORATION OF MAINE.

JOINTED WELTING.

1,353,251. Specification of Letters Patent. Patented Sept. 21, 1920.

Application filed March 26, 1919. Serial No. 285,349.

To all whom it may concern:

Be it known that I, CHESTER D. LIBBY, a citizen of the United States, residing at Malden, in the county of Middlesex and State of Massachusetts, have invented certain new and useful Improvements in Jointed Welting; and I do hereby declare the following to be a full, clear, and exact description of the invention, such as will enable others skilled in the art to which it appertains to make and use the same.

The present invention relates to jointed welting and to a method of making the same.

15 Welting for use in the manufacture of boots and shoes is ordinarily supplied in the form of long strips which are composed of a plurality of relatively short strips of leather, the skived ends of which overlap and are secured together by cement. These jointed ends are subjected not only to direct tension strains but also to the bending strains resulting from bending the welting in its own plane or edgewise as it is applied 20 to the rounded or curved outline of a shoe. Unless the ends of the strips are firmly secured together they are liable to separate or break apart, particularly at the toe portion of a shoe where the bending is the sharpest.

25 The object of the present invention is to produce a jointed welting which shall be capable of resisting not only the usual direct tension strains without danger of separation at the joints but also the bending strains incident to the attachment of the welting to the rounded or curved portions of a shoe.

To the above end the invention consists in the welting hereinafter described and claimed.

30 The preferred embodiment of the invention is illustrated in the accompanying drawings, in which Figure 1 is a perspective view of a portion of a strip of welting showing the improved joint; Fig. 2 is a plan view of one end of one of the short strips of which the welting is composed, showing the skived and grooved face which is to be united with a corresponding face on another similar strip; Fig. 3 is a section on the line 3—3 of Fig. 2; Fig. 4 is a plan view of a portion of a strip of welting showing the improved joint; Fig. 5 is a section on the line 5—5 of Fig. 4, illustrating the interlocking of the grooved ends; and Fig. 6 35 illustrates in section a modification where

only one of the jointed ends of the welt strip is grooved.

As shown in the drawings the short strips 8, of which the welting is composed, are skived or scarfed at their ends in the usual manner as indicated at 9 so that the thickness of the strip is tapered longitudinally. The skived faces 9 of the short strips are then grooved or fluted so as to produce a series of alternate grooves 10 and ridges 11 65 extending lengthwise of the strip. The skived and grooved faces are then coated with a suitable adhesive substance and pressed together so that the ridges of each face will fit into the grooves of the opposed 70 face.

It will be observed that grooving the skived ends of the welt strips not only increases the surfaces to which the cement may be applied and may adhere but by the 75 interlocking, as it were, of the grooves and ridges, lateral or angular slipping of the joined ends is prevented when the welting is bent edgewise to conform to the curvature of the shoe, particularly around the toe 80 portion.

In Fig. 6 is illustrated a modification of the present invention. This figure shows in cross-section the joint between two adjacent welt strips, only one of which is provided 85 at its joined end with grooves and ridges, the contacting face of the other welt strip being substantially plane. With this modified form of the present invention not only is the cementing surface on one of the strips 90 increased, but the cement, which is applied to the grooved face in a quantity sufficient to fill the grooves, hardens and uniting with the plane face of the other strip forms practically a series of ridges and grooves which 95 interlock with the grooves and ridges integrally formed on the other strip and securely hold the joined strips together.

While the present invention has been shown and described in its preferred form, 100 the invention is not limited thereto but may be embodied in other constructions and arrangements. Where in the claims the term "longitudinal" is employed, this is to be understood as meaning a direction generally 105 lengthwise of the welt strip so as to prevent angular yielding or slipping of one attaching face upon the other as distinguished from transverse grooves or ridges designed and acting to resist direct tension strains. 110

Having thus described the present invention, what is claimed is:—

1. An article of manufacture consisting of a strip of welting formed of a plurality of shorter strips with their ends overlapping and secured together by adhesive material, the overlapping portions of the surface of one of said strips being provided with longitudinal grooves in its contacting portion.
2. An article of manufacture consisting of a strip of welting formed of a plurality of shorter strips with their ends overlapping and secured together and provided on their opposed overlapping contacting surface portions with interlocking longitudinal ridges and grooves.

3. An article of manufacture consisting of a strip of welting formed of a plurality of shorter strips with their ends overlapping and cemented together, the contacting surfaces being beveled and provided with longitudinal grooves.

4. An article of manufacture consisting of a strip of welting formed of a plurality of shorter strips with their ends overlapping and cemented together, the contacting surfaces being beveled and provided on their opposed overlapping surface portions with a plurality of substantially parallel and relatively narrow interlocking longitudinal ridges and grooves extending substantially the length of the overlapping surfaces.

CHESTER D. LIBBY.
